UNITED STATES PATENT OFFICE

143,233

DESIGN FOR A COMBINED BOTTLE OPENER AND CUTTER OR SIMILAR ARTICLE

James Gordon Moore, Los Angeles, Calif.

Application July 3, 1945, Serial No. 120,495

Term of patent 7 years

(Cl. D22—2)

To all whom it may concern:

Be it known that I, James Gordon Moore, a citizen of the United States, residing in Los Angeles, in the county of Los Angeles, State of California, have invented a new, original, and ornamental Design for a Combined Bottle Opener and Cutter or Similar Article, of which the following is a specification, reference being had to the accompanying drawing forming a part thereof.

Figure 1 is a side view of a combined bottle opener and cutter embodying my new design.

Figure 2 is a view from the opposite side of

that shown in Figure 1, showing the bottle opener and cutter in relative closed position.

Figure 3 is a view similar to Figure 2 but illustrating the cutter in relative open position with respect to the bottle opener.

Figure 4 is a view of the cutter in open position in the same manner but from the opposite side of that shown in Figure 3.

I claim:

The ornamental design for a combined bottle opener and cutter or similar article, as shown.

JAMES GORDON MOORE.
